DESIGN FOR A RUG

Alfons Bach, New York, N. Y., assignor to Bigelow
Sanford Carpet Co., Inc., a corporation of Massachusetts

Application December 8, 1934, Serial No. 54,356

Term of patent 7 years

To all whom it may concern:

Be it known that I, Alfons Bach, a citizen of the United States, residing at New York, in New York County, and State of New York, have invented a new, original, and ornamental Design for a Rug, of which the following is a specification, reference being had to the accompanying drawing, forming part thereof, in which a plan view of the rug is shown.

The drawing shows the complete rug.

I claim:

The ornamental design for a rug, substantially as shown and described.

ALFONS BACH.
